(57) **CLAIM**

The ornamental design for a multi-channel product display shelf, as shown and described.

DESCRIPTION

FIG. 1 is a front perspective view of a multi-channel product display shelf according to the present invention;

FIG. 2 is a front view of the multi-channel product display shelf shown in FIG. 1;

FIG. 3 is a rear view of the multi-channel product display shelf shown in FIG. 1;

FIG. 4 is a right side view of the multi-channel product display shelf shown in FIG. 1;

FIG. 5 is a left side view of the multi-channel product display shelf shown in FIG. 1;

FIG. 6 is a top view of the multi-channel product display shelf shown in FIG. 1; and,

FIG. 7 is a bottom view of the multi-channel product display shelf shown in FIG. 1.

The parallel diagonal shading lines in FIGS. 1-3 at the front of the multi-channel product display shelf indicate transparency.

1 Claim, 5 Drawing Sheets
